CLAIM

The ornamental design for a flowmeter—sample conditioner, as shown and described.

DESCRIPTION

FIG. 1 is a perspective view of the flowmeter—sample conditioner which is the subject of the present design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The letters/numerals appearing in FIGS. 4 and 6 are for the purpose of illustration only and do not form part of the claimed design.
